FLOOR CRANE

Filed Jan. 14, 1922.

2 Sheets-Sheet 2

UNITED STATES PATENT OFFICE.

WILLIAM R. BEATTY, OF HAMMOND, INDIANA.

FLOOR CRANE.

Application filed January 14, 1922. Serial No. 529,222.

To all whom it may concern:

Be it known that I, WILLIAM R. BEATTY, a citizen of the United States, residing at Hammond, in the county of Lake and State 5 of Indiana, have invented certain new and useful Improvements in Floor Cranes, of which the following is a specification, reference being had therein to the accompanying drawings.

- 10 This invention relates to floor cranes, and the object of the invention is the construction of a simple and efficient floor crane that comprises a minimum number of parts and which is durable, as well as easy to operate.
- 15 Another object of the invention is the simplification and improvement of the floor crane disclosed in my prior United States Patent, No. 1,333,200, patented March 9, 1920.
- 20 With these and other objects in view, my invention comprises certain novel combinations, constructions and arrangements of parts as will be hereinafter described, illustrated in the accompanying drawings, and 25 more particularly pointed out in the appended claim.

In the drawings:

Figure 1 is a view in side elevation of a floor crane constructed in accordance 30 with the present invention.

Figure 2 is a front view of the same.

Figure 3 is a sectional view, taken on line 3—3, Fig. 1, and looking in the direction of the arrows.

35 Figure 4 is a view in elevation of the standard structure only.

Referring to the drawings by numerals, 1 designates the wheeled platform of my apparatus carrying the standard 2 and its 40 cooperating parts. The standard 2 is curved at its upper end so as to produce an overhanging, upper end 3. The lower end of standard 2 is integral with base plate 4, which plate 4 is attached to the wheeled 45 platform 1 by suitable fastening means such as bolts 5.

Integral with the lower portion of the standard is a horizontal arm 6, which arm 6 is provided with a bearing 7, in which 50 bearing 7 is journalled the worm 8, which worm 8 is rotated by means of handle 9. A vertical reinforcing web 10 is integral with standard 2 and the arm 6, and a vertical reinforcing rib 11 is integral with web 55 10 and arm 6, for strengthening the structure; the reinforcing rib 11 is positioned at

right-angles to the web 10, and is connected at its lower end to base plate 4 and at its upper end to arm 6.

A lower reinforced bearing 12 is integral 60 with the standard 2 immediately above arm 6. Journalled in bearing 12 is drum 13, and secured at one end of drum 13 is worm gear 14; worm gear 14 meshes with worm 8, whereby, when handle 9 is rotated, the 65 drum 13 will be operated to wind, or unwind the rope or cable 15, at the will of the operator.

An intermediate reinforced bearing 16 is formed integral with the standard 2, and 70 journalled upon bearing 16 is pulley or flanged roller 17, over which the rope or cable 15 passes.

Upper bearing 18 carries pulley 20, over 75 which the rope or cable 15 travels. Eye bolt 21 is fastened to the outer, overhanging end 3 of standard 2, and rope or cable 15 is fastened at one end of the eye bolt 21, said rope or cable being passed around pulley 22, which pulley carries the hook 23. 80

In operation the operator rotates handle 9 for winding the rope or cable 15 upon drum 13, or by reversing the movement of the handle, the rope or cable can be unwound, hence, letting hook 23 be lowered to 85 the position for attachment to the load to be lifted and conveyed by the apparatus. When the operator stops rotating the handle 9, the worm gear will stop rotating, thus locking the drum against rotation. 90

While I have described the preferred embodiment of my invention, and have illustrated the same in the accompanying drawings, certain minor changes or alterations 95 may appear to one skilled in the art to which this invention relates, during the extensive manufacture of the same and I, therefore, reserve the right to make such alterations or changes as shall fairly fall within the scope of the appended claim. 100

What I claim is:

A floor crane comprising a base, a standard rigid upon said base and extending upwardly and having its upper end portion curved to provide an overhanging upper end portion, bearings extending from opposite sides of the lower portion of said standard, a drum positioned between said bearings and having a shaft rotatably mounted in said bearings and extending beyond one of the 105 bearings, a worm gear carried by the extended end of the shaft of said drum, a web ex-

tending from the lower portion of said standard, arms extending from said web and terminating in bearings positioned beneath said worm gear, a drive shaft rotatably 5 mounted in the lower bearings, a worm carried by said drive shaft between the lower bearings and engaging said worm gear to rotate said drum when the drive shaft is turned, a depending eye at the up- 10 per free end of said standard, guiding pul- leys carried by said standard at points intermediate its length, a cable wound upon said drum and carried upwardly in engagement with the guide pulleys and connected with said eye, and a hook carrying pulley 15 block upon said cable between the eye and first guide pulley.

In testimony whereof hereunto affix my signature.

WILLIAM R. BEATTY.
